UNITED STATES PATENT OFFICE.

JAMES N. NEWMAN, OF RIVERSIDE, CALIFORNIA.

BALING-PRESS.

SPECIFICATION forming part of Letters Patent No. 638,644, dated December 5, 1899.

Application filed July 27, 1898. Serial No. 686,993. (No model.)

To all whom it may concern:

Be it known that I, JAMES N. NEWMAN, a citizen of the United States, residing at Riverside, in the county of Riverside and State of California, have invented certain new and useful Improvements in Baling-Presses; and I do hereby declare the following to be a full, clear, and exact description of the invention, such as will enable others skilled in the art to 10 which it appertains to make and use the same.

This invention relates to baling-presses, particularly to that class known as "windlass;" and, generally stated, it consists of a frame supporting the baling-box at the rear having 15 communication at its front end with a feeding-chamber, together with a plunger, to which the ends of draw ropes, cables, or chains are connected on opposite sides and passed over rear pairs of pulleys, the rear looped portions 20 of said ropes, cables, or chains being returned through guides toward the front of the press and attached to draft devices of a similar nature which run forwardly and wind to and from the opposite portions of a windlass, the 25 latter also having an intermediate rope, cable, or chain winding on and from the same in a direction reverse to said draft devices and attached to the plunger.

The invention further consists of the construction, arrangement, and combination of the several parts, which will be more fully hereinafter described and claimed.

Most, if not all, baling-presses as heretofore constructed have been of an expensive 35 nature and the cost thereof far in excess of the means of the average farmer and comparatively few acquire the ownership of this class of farming machinery. If possessed, they require a number of operators and usually 40 an expenditure of a large amount of horse-power or other costly motor-power, with the accompanying injurious effect on the animals employed to drive the mechanism or requiring the services of a skilled mechanic to operate 45 the motor and also demanding considerable mechanical knowledge to operate the machine and maintain it in such condition structurally as to cause the effectual performance of the desired work. Hence it has been 50 customary for the majority of farmers to hire their baling done and await the convenience of the owner of a press to bale the hay or

straw and put it up in the desired condition for storage or other purposes. Through the medium of the improved form of press it is 55 intended to overcome the disadvantages enumerated and many other additional ones by producing a baling-press of simple construction and effective operation which can be cheaply purchased and requiring a minimum 60 number of operators to carry on the baling operation and dispense with the horse or other power by relying on manual exertion to obtain the necessary pressure.

In the accompanying drawings, Figure 1 is a 65 perspective view of a baling-press embodying the invention. Fig. 2 is a longitudinal vertical section of the same. Fig. 3 is a transverse vertical section on the line *x x*, Fig. 2. Fig. 4 is a detail perspective view of the 70 plunger. Figs. 5, 6, and 7 are detail views of modifications of the means for operating the windlass.

Referring to the drawings, wherein similar numerals are utilized to indicate corresponding parts in the several views, the numeral 1 designates a frame comprising pairs of front and rear end posts 2 and 3 and intermediate pairs of posts 4 and 5, all of which are tied at their upper ends by cross-strips 6 and connected by longitudinal brace-rails 7, which resist the strain. The rails 7 are located on opposite sides of the press and engage all the posts, being fitted to the intermediate posts 4 and 5 by the formation of mortises 8 and 85 bearing against the front and rear end posts in such manner as to prevent displacement thereof by the drawing strain longitudinally exerted. Nearer the lower ends of the said posts cross-strips 9 are secured, on which is 90 rested a flooring 10, and connected to the posts 2 and 4 are supplemental longitudinal braces 10°. Between the posts 5 and 3 a baling-box 11 is formed by surrounding boards, which have spaces 12 between them on opposite 95 sides, and at the rear end of said baling-box a suitable tail-board 13 is removably fitted and is of sufficient strength to resist the pressure brought to bear thereagainst. The baling-box 11 communicates with a feed-chamber 14, which is open at the top, and in the opposite sides 15 of said chamber are upper and lower pairs of parallel slots 16, extending longitudinally and terminating at the posts 5.

Movably mounted in the feed-chamber is a vertically-disposed plunger 17, preferably constructed of vertical strips having upper and lower battens 18, to which transversely-extending arms 19 are bolted, and having apertured projecting ends 20 movably mounted in the slots 16. The battens 18 and arms 19 are connected at the center by a vertical bar 21, and thereto is secured the front end of a rope, 5 cable, or chain 22, which extends forwardly and surrounds a windlass or roller 23, mounted in suitable bearings on the posts 2 and, as shown by Fig. 1, having a crank-handle 24 at one side for rotating the same. The rope, 10 cable, or chain 22 winds on and unwinds from the windlass at the lower portion thereof and is sufficiently long to permit the plunger to move up to the mouth of the baling-chamber. 15

To the projecting apertured ends 20 of the 20 arms 19 the two ends of a looped rope, cable, or chain 25 are secured and then extend rearward through guide-openings 26 in the posts 5 and 3 and over opposite pairs of sheaves or pulleys 27 and back through adjacent openings 28 in the posts 3, leaving the looped ends on the front sides of the said posts. To arrange the rope, cable, or chain 25 on each side of the press in the manner stated, the ends are first passed through the openings 20 toward the rear, then over the pulleys or sheaves 27 and forwardly through the openings 26 in the posts 3 and 5, and afterward connected to the said projecting ends 20 of the arms 19. The sheaves or pulleys 27 are so mounted on 25 the posts 3 that they will be in a plane about the center of the rear end of the baling-box 11, and to the looped portions on the front of the posts 3 draft ropes, cables, or chains 29 are attached and run forwardly through guide- 30 openings 30 in the posts 5 and 4 to opposite sides of the windlass or roller 23 and winding on and from the latter at the upper portion or reversely to the rope, cable, or chain 22 which intermediately engages the said wind- 35 lass or roller.

In arranging the press for baling purposes the plunger is drawn forwardly to its full extent and the tail-board 13 is positioned at the rear end of the baling-box 11. A charge of 40 hay or straw is then deposited in the feeding-chamber 14, and the windlass 23 is rotated in such direction that the draft ropes, cables, or chains 29 will be wound thereon and the rope, cable, or chain 22 unwound therefrom, and 45 thereby draw the said plunger toward the rear and force the charge of hay or straw into the baling-box. A reverse rotation of the windlass or roller 23 will again move the plunger forwardly and leave the feeding-chamber 50 clear for the reception of a second charge of hay or straw, when the plunger will be again drawn toward the rear, and so on successively until a sufficient amount of hay or straw has been compressed by the plunger in the baling- 55 box. At the time that the bale has reached the proper dimension the plunger will be slackened slightly until the tie wires or cords 60

are secured on the bale by rotating the windlass or roller 23 in the proper direction to bring the plunger forward, relieving the pressure of said plunger and permitting the insertion of further charges of hay or straw to form a second bale, that shoves the first gradually outward from the bale-box and after the tail-board 13 has been disconnected. 70

The baling operation can be readily carried on in the manner set forth, and for ordinary purposes the exertion of one man or operator on the windlass through the medium of the crank-handle 24 will be sufficient to 80 attain the desired result. As shown in Fig. 5, two crank-handles 31 and 32 might be used, and as a further convenience the ratchet mechanism 33 might also be employed to lock the windlass under certain conditions and prevent the plunger from slipping forwardly or away from the mouth of the baling-box. In Fig. 6 the end of the windlass or roller is formed with apertures 34 to receive hand-levers 35, which can be utilized to give greater 90 pressure to the plunger in forming more compact bales than ordinarily desired, and to increase the power by further mechanism the end of the windlass or roller, as shown by Fig. 7, can have a toothed head or gear 36 secured 95 thereto of less dimension than and meshing with an adjacent pinion 37. Other changes might be shown and described for attaining a variation in the degree of pressure; but those set forth sufficiently display the variations that might be resorted to. 100

By the formation of the openings 26, 28, and 30 in the opposite pairs of uprights or posts the use of pulleys or sheaves is entirely dispensed with and the cost of manufacture 105 of the press is materially reduced.

It will be observed from the foregoing disclosure that the manufacture or repairing of the improved press does not require the services of an exceptionally-skilled mechanic, as 110 the parts are few in number and simple in construction, but at the same time are capable of resisting or standing a great amount of pressure without injury, and to prevent the several posts and pieces of the frame and baling-box from springing bolts are used, which are passed through the said members, and, further, by this means also substituted parts can be easily applied to replace those which become worn without destroying the entire 115 press. 120

Having thus described the invention, what is claimed as new is—

A baling-press of the horizontal type comprising spaced vertical supports, centrally-disposed longitudinal rails extending the full length of the press and connecting the vertical supports in series and alining transversely, a baling-chamber having longitudinal slots in its sides above and below the longitudinal 125 rails, a follower having upper and lower transverse arms with their end portions projecting through the longitudinal slots of the baling-chamber, a vertical bar connecting the arms 130

centrally, a windlass placed with its top side about in the plane of the longitudinal rails, a return-rope adapted to wind centrally upon the windlass and having connection with the 5 aforesaid vertical bar at a middle point, side ropes arranged adjacent to the longitudinal rails and passing through openings in said vertical supports and having their rear ends adapted to wind upon the end portions of the 10 windlass, and looped ropes attached at a middle point to the free ends of the side ropes and passing over direction-pulleys thence forward above and below the longitudinal rails

parallel therewith and through openings in the vertical supports and attached to the projecting terminals of the follower-arms and disposed to advance the follower in parallel planes and prevent binding of its arms in the longitudinal slots, substantially as set forth. 15

In testimony whereof I affix my signature 20 in presence of two witnesses.

JAMES N. NEWMAN.
